The ornamental design for a support for a hand held hair dryer or styling implement, as shown and described.

DESCRIPTION

FIG. 1 is a perspective view of a support for a hand held hair dryer or styling implement showing my new design;

FIG. 2 is a front elevational view thereof;

FIG. 3 is a rear elevational view thereof;

FIG. 4 is a left side elevational view thereof, the side opposite being a mirror image of the side shown;

FIG. 5 is a top plan view thereof; and,

FIG. 6 is a bottom view thereof.

FIG.1.

FIG. 2.

FIG. 3.

FIG. 4.
